(57) **CLAIM**

The ornamental design for a wireless communication terminal, as shown and described.

DESCRIPTION

FIG. 1 is a front elevational view of a wireless communication terminal showing our new design;
FIG. 2 is a rear elevational view thereof;
FIG. 3 is a left side view thereof;
FIG. 4 is a right side view thereof;
FIG. 5 is a top plan view thereof;
FIG. 6 is a bottom plan view thereof;
FIG. 7 is a front and right side perspective view thereof;
FIG. 8 is a top, rear and left side perspective view thereof;
and,
FIG. 9 is a bottom, rear and right side perspective view thereof.

The broken lines in the drawings depict portions of the wireless communication terminal that form no part of the claimed design. The oblique shade lines in the drawings represent a reflective surface.
